United States Patent Office

Des. 188,986
Patented Oct. 11, 1960

188,986

POST CAP

Wiley C. Duncan, P.O. Box 1703, Harlingen, Tex.

Filed Nov. 3, 1959, Ser. No. 58,194

Term of patent 3½ years

(Cl. D29—23)

Fig. 1 is a front elevational view showing my new design for a post cap;

Fig. 2 is a rear elevational view thereof;

Fig. 3 is a side elevational view thereof; and

Fig. 4 is a top plan view thereof.

I claim:

The ornamental design for a post cap, as shown.
